(57) **CLAIM**

The ornamental design for an end cap for baton, as shown.

DESCRIPTION

FIG. 1 is a sectional view of an end cap for a baton, showing my new design;

FIG. 2 is a top view of the end cap;

FIG. 3 is a side view of the end cap;

FIG. 4 is a side view of the end cap, shown on a baton;

FIG. 5 is a perspective view of the end cap, shown on a baton;

FIG. 6 is a close-up perspective view of the end cap shown on the baton;

FIG. 7 is another perspective view of the end cap; and,

FIG. 8 is another perspective view of the end cap.

The end cap is rotationally identical, that is, the visual appearance is the same from all sides around the axis.

The broken line showing of environment in the drawings is included for the purpose of illustrating only and forms no part of the claimed design.
